(57) **CLAIM**

I claim the ornamental design for a fixed position RF electrode, as shown and described.

DESCRIPTION

FIG. 1 is a perspective view of a fixed position RF electrode showing my new design;

FIG. 2 is a side view thereof;

FIG. 3 is a front view thereof;

FIG. 4 is a perspective view thereof;

FIG. 5 is a top view thereof; and,

FIG. 6 is a bottom view thereof.

The broken lines shown in the drawings represent portions of the fixed position RF electrode that form no part of the claimed design.

All surfaces not shown form no part of the claimed design.
